Harry Jacobson
ATTORNEY.

UNITED STATES PATENT OFFICE.

BÉLA ZSARNAY, OF BELLEVILLE, NEW JERSEY, ASSIGNOR OF ONE-HALF TO ABRAHAM LEWIS, OF NEWARK, NEW JERSEY.

POLISHER AND GRINDER FOR WOOD AND METAL MANUFACTURERS.

Specification of Letters Patent. Patented Aug. 23, 1921.

1,388,231.

Application filed March 26, 1920. Serial No. 368,829.

To all whom it may concern:

Be it known that I, BÉLA ZSARNAY, citizen of the United States, and resident of Belleville, in the county of Essex and State of New Jersey, have invented certain new and useful Improvements in Polishers and Grinders for Wood and Metal Manufacturers, of which the following is a specification.

This invention relates to polishing and abrading machines and has for its object the provision of a compact and readily accessible and adjustable machine of this type.

For the accomplishment of the above and other objects, I employ the mechanism shown in its preferred form in the accompanying drawings, in which,

Figure 1 is a front view and partial section, on line 1—1 of Fig. 2, of the major part of my machine. Fig. 2 is an end view showing the bar polishing and forwarding mechanism. Fig. 3 is a section on line 8—8 of Fig. 1.

In the practical embodiment of my invention, pulley 1 on shaft 2, which is supported by hangers 3, is driven from a source of power not shown and rotates said shaft 2 and the pulleys mounted thereon through which the various mechanisms of my machine are driven.

30 A table 4, suitably supported on legs 5, has mounted thereon at one end, frames 6, 7, 9, and 10 (Figs. 1, 2, and 3) which inclose mechanism for grinding and polishing both sides of the work as 98 and for forwarding said work through the polishing means. A top cover 8, having opening 11 for allowing the insertion of work into the machine, is suitably fastened over said frames for completely inclosing said mechanism. Two of

40 such mechanisms are shown, both exactly alike except that they are reversed end for end with respect to each other, (Fig. 2) the rear end of one being placed in juxtaposition to the front end of the other, so that a description of one will suffice for both.

45 Pulley 12 on shaft 2 drives pulley 13 of one of said mechanisms through belt 15, while pulley 14 on shaft 2 drives a similar pulley 13 on the other of said mechanisms through belt 16. Gear wheel 17 is mounted on the same shaft 18 on which pulley 13 is mounted and meshes with gear 19 on shaft 20. A second gear 100 is removably mounted on shaft 20, for allowing a gear of different size to be mounted on said shaft, whereby

the speed of rotation of the entire mechanism may readily be changed for fast or slow grinding. A stud 21 supported from frame 7, has loosely mounted thereon for easy removal therefrom when changes in speed are desired, gear wheel 22 for engaging gear wheel 100, crank disk 23 being secured to said wheel 22. Connecting rod 24 attached at pin 25 to disk 23 is secured at its upper end at crank pin 26 to crank disk 27 mounted on shaft 28. A pulley 29 on said shaft 28 drives pulley 30 on shaft 31 through belt 32, while pulley 33 at the end of shaft 28 opposite to that on which pulley 29 is mounted, drives pulley 34 on shaft 35 through belt 36. Similarly, pulley 37 on shaft 38 is driven by pulley 39 on shaft 20 by means of belt 40, a cylindrical roll 41 covered with polishing or abrading material such as glass, sand, flint, emery or the like, being mounted on said shaft 38, said grinding or polishing material being comparatively coarse.

A similar roll 42 is mounted on shaft 28, while rolls 43 and 44 are mounted on shafts 18 and 31 respectively, and are covered with material more finely divided than that on rolls 41 and 42. Rolls 45 and 46 on shafts 20 and 36 respectively are covered with leather or other durable polishing material for giving the final finish to the work. For adjusting the distance between the vertical sets of rolls to take work of different thicknesses, shafts 28, 31 and 36 carrying the outer sets of rolls, are mounted in a movable frame having a body portion 52 and two projecting flanges 53 for supporting said shafts near the ends thereof, suitable slots 54 in frames 6 and 7 being provided to allow movement of the ends of said shafts in said frames during adjustment.

Guide rods 50 are supported in frames 9 and 10 and carry springs 51 for exerting sufficient pressure on shaft-carrying frame 52 to hold said frame in its adjusted position. Adjusting screws 47 having wing heads 48 thereon are arranged in frame 10 to move shaft-carrying frame 52 toward the center line between the two mechanisms against the action of springs 51.

I have also indicated as mounted on the table 4 and operated by shaft 2 a reciprocable polishing block 55 and endless belt 66. Block 55 is suitably guided on table 4 and is reciprocated by a link 57 connected to a

- crank disk 58 as at 58'. The crank disk 58 is mounted on a shaft 59 in a standard 60 and is driven by a belt 62, looped thereover and over a pulley 63 on the shaft 2. The 5 block may be guided on table 4 by screws 64 passing up through a suitable slot in the table and fixed to the underside of the block, these screws having flanges 65 of sufficient diameter to overlap the edges of the slot.
- 10 The belt 66 is indicated as looped over pulleys 67 and 70, the latter of which is fixed on shaft 2, pulley 68 being fixed on a shaft 68 journaled in bearings 69 on the table 4.

15 Suitable provision may be made for the removal of the dust formed by the polishing process. A pair of ducts 94 having intake openings therein positioned under suitable openings in table 4 are here shown, these ducts communicating with any suitable suc-

20 tion device.

The operation of my improved machine is as follows:

25 Screws 47 being turned by means of the wing screw heads 48 sufficiently to make the space between one of the vertical sets of rolls 41, 43 and 45 and the adjustable set of rolls 42, 44, and 46, equal to the thickness of the finished work, pulley 1 is rotated, imparting motion to all of the various sub-30 mechanism of my machine. It will be noted that by means of the peculiar connections hereinbefore described, all of said rolls will be rotated in the same direction. The sizes of the various pulleys are such, however, 35 that one set of rolls rotates somewhat faster than the other set, so that the tendency of the rolls is to gradually forward any work as 98, inserted through opening 8 in between

said rolls, downwardly, through a suitable opening in table 4, without much effort on the part of the operator, it being obvious that the tendency of rolls which are made to rotate in the usual manner, to drag the work out of the hands of the operator, is eliminated. The work ejected from the rolls is 45 polished before ejection, by leather rolls 36 and 45.

What I claim is:

1. In a polishing machine, a set of revolu- 40 ble rolls adapted to engage one side of the work, a second set of revoluble rolls spaced from said first set and adapted to engage the opposite side of the work, a movable frame carrying said second set of rolls, rods on which said frame is slidably mounted, springs 50 on said rods for pressing said second set away from said first set of rolls, and screws for moving said frame toward said first set of rolls.

2. In a polishing machine, a set of revolu- 60 ble rolls adapted to engage one side of the work, a second set of revoluble rolls spaced from said first set and adapted to engage the opposite side of the work, a movable frame carrying said second set of rolls, rods on 65 which said frame is mounted, springs on said rods for pressing said second set away from said first set of rolls, screws for moving said frame, and means for rotating said set of rolls in the same direction and for 70 rotating one set of said rolls faster than the other set.

Signed at Belleville, in the county of Essex and State of New Jersey, this second day of March, A. D. 1920.

BÉLA ZSARNAY.
